Application December 20, 1938, Serial No. 246,837

5 Claims. (Cl. 62—91.5)

This invention relates to refrigeration and more particularly concerns an improved refrigerating method and system employing an evaporable refrigerant of the type that sublimes directly from the solid to the gaseous state, such as solid 5 carbon dioxide.

When solid carbon dioxide evaporates or sublimes to the gaseous state, heat is absorbed at such a rapid rate that the medium to be cooled, which may be the space within a refrigerator 10 cabinet, is quickly reduced to a temperature far below the desired range. In accordance with the present invention, it is proposed to provide a refrigerating method and system in which the cooling effect produced by the gasification of 15 solid carbon dioxide or like material is effectively and economically controlled whereby the medium to be cooled can be maintained at the desired temperature and the evaporation of the refrigerating material can be suitably retarded in conformity with the refrigerating load imposed. To this end, the system of the invention includes a conduit circuit for conducting brine or other heat transferring liquid to low freezing point in successive heat exchanging relation with the evaporating carbon dioxide and the medium to be cooled, and further includes improved means for controlling the rate of flow of the liquid through this circuit.

A further primary object of the invention is the provision of a system of the type described which is portable and which may be used on trucks, buses, railway cars and other conveyances where it is subjected to considerable vibration and agitation. To this end, the improved system employs a conduit circuit for the heat transferring liquid such as brine, which circuit is entirely closed and thereby completely isolated not only from the atmosphere but from the evaporated gaseous refrigerant as well. The system of the invention incorporates mechanical means such as a pump or impeller for positively circulating the heat transferring liquid through its closed circuit, and this pump is driven by a mechanical power producing means motivated by the pressure of the refrigerant gas evolved from the solid refrigerant as it evaporates to produce the heat absorbing effect.

Another object of the invention is the provision of a system of the type described incorporating improved means for controlling the circulation of the brine or other heat transferring medium in accordance with the temperature of the cabinet or other medium to be cooled. The solid refrigerant material is confined in a sealed

chamber from which the gas under pressure is carried by a suitable duct to the power producing means which drives the liquid circulating pump. In accordance with the invention, the circulation of the brine or liquid is controlled by a thermostatic device which regulates the gas pressure delivered from the solid refrigerant chamber to the pump driving means. In a preferred embodiment of the invention, the thermostatic means acts, when the cabinet or other medium has been cooled to the desired low temperature, to vent the duct supplying gas to the pump driving means whereby the pressure available to operate the pump is reduced and the pump is stopped. In some cases, it is preferred to provide suitable means for restricting the flow of gaseous refrigerant from the solid refrigerant chamber when the duct supplying the pump driving means is so vented. In this manner, the gas pressure in the solid refrigerant chamber is not unduly reduced when the operation of the pump is discontinued or retarded by venting its gas supply duct.

Various additional objects, advantages and characteristic features of the invention will be pointed out or will become apparent in connection with the description of certain embodiments thereof.

In accomplishing these and other objects of 30 the invention, I have provided the improved details of construction, the preferred and alternative forms of which are illustrated in the accompanying drawings, wherein—

Fig. 1 is a vertical, cross section of a refrigerating plant embodying the present invention in 35 one of its preferred forms.

Fig. 2 is a vertical cross section, taken on the line 2—2 in Fig. 1.

Fig. 3 is an enlarged sectional detail through 40 the cooling coils, as seen on the line 3—3 in Fig. 1, particularly illustrating the overlying plate for supporting the refrigerant thereon.

Fig. 4 is a similar cross sectional detail, showing coils of a different cross sectional form.

Fig. 5 is a detail of the lid of the refrigerant 45 chamber, showing its clamping and sealing means.

Fig. 6 is an enlarged, central cross sectional view of the refrigerant pump.

Fig. 7 is a view illustrating details in section 50 of the pump and the gas control valve with its thermostatic control.

Fig. 8 is a plan view of the cooling coils, as disposed in the bottom of the refrigerant chamber.

Fig. 9 is a view illustrating an alternative, one-pipe system, utilizing pump action for recharging the cooling coils.

Fig. 10 is an enlarged sectional detail of the valve devices employed for controlling flow of gas to the pump.

Fig. 11 is a sectional view of a pump of alternative form.

Fig. 12 is a sectional detail of still another alternative form of pump, adapted for continuous circulation of the liquid medium.

Figs. 13, 14 and 15 are diagrammatic illustrations of alternative forms of construction, wherein the generated gas is discharged directly into the liquid circulating pipes to create a forced circulation in the recharging of the cooling coils.

Briefly described, the present systems are designed to be associated with cabinets of usual types employed for refrigeration, adequately insulated against heat transfer from external sources, and provided with suitable air-tight doors to give access to the interior thereof. It is also contemplated that the front wall of the cabinet be equipped with glass windows for display purposes as is common in many refrigerators of the market types.

Within the cabinet is a compartment for the solidified refrigerant, suitably insulated from the storage space and within which compartment is disposed, upon its bottom or floor, a coil of tubing within which the liquid medium or "brine" is circulated for cooling. A pump is interposed in the pipe system of the circulated liquid medium, and this pump is operated by the gas generated by the evaporation of solidified refrigerant, as it takes on heat from the coil.

The refrigerant compartment has a lid, or cover, of substantial dimensions to permit easy and quick recharging of the compartment, and the lid may be applied in an air-tight seal to prevent the escape of the generated gas.

Referring more in detail to the drawings—

As seen in Figs. 1 and 2, the present mechanism is embodied in a cabinet, designated in its entirety by the reference numeral 10, comprising outer and inner wall linings 11 and 12 of sheet metal between which is disposed a filler of suitable heat insulating material 13. This cabinet, as seen in Fig. 2, is provided in its top wall with an opening 14 to which is fitted an air-tight door 15; the door being hinged at 16 to open upwardly, and a latch being provided, as at 17, to hold it tightly closed.

In the present instance, I have shown the cabinet as being provided with a display window 20 in its front wall, and this window comprises a plurality of glass plates 20a, 20b and 20c, spaced apart so as to provide intermediate spaces, whereby to minimize heat transfer from the exterior to the interior of the cabinet. The spaces between the glass plates preferably are filled with carbon dioxide gas to eliminate frosting of the glass.

Disposed within the refrigerator is a metallic container, designated in its entirety by the reference numeral 25. This container is here shown to be of rectangular form, but may be round or of other suitable shape, and it is constructed with outer and inner wall linings 26 and 27, of sheet metal, between which is disposed a layer of heat insulating material 28. It will be noted, by reference to Fig. 1, that the outer lining 26 is formed with an inturned flange about its top portion, then is turned upwardly in line with the inner lining 27, and that a lid 28 is removably disposed

upon the extended edges; the lid having depending flanges that overlap these edges, and within the flanges is fitted with a sealing gasket 31 of rubber or other suitable sealing material, as noted in Fig. 5.

Fixed permanently to the inturned upper edge flanges of the outer wall lining, at opposite sides of the lid 28 are upwardly directed brackets 32, provided with laterally opening notches 33, as noted in Fig. 5, wherein the opposite ends of a lid clamping rod 34 are rotatably contained. As seen in Figs. 1, 2 and 5, this clamping rod 34 is substantially straight, and is provided near its ends with eccentrically formed cam portions 35, 10 15 adapted to be pressed into clamping contact with flat leaf springs 35' disposed against the top of the cover 30 near opposite edges, to press the cover tightly against the top edges of the container walls 27. This clamping action is effected by rotation of the rod through the leverage provided by a handle 36 that is fixed to the rod at a medial point, and extends perpendicularly to the formed cam portions 35, as shown in Fig. 5. It will be understood that with the compartment 25 sealed, gas generated by the evaporation of the solidified refrigerant will be confined under pressure.

A gas discharge tube, or pipe, 40 leads from the compartment 25 to a valve housing 41, which contains a needle valve controlled by a thermostat; the thermostat being designated in its entirety in Fig. 2 by the reference numeral 42. A pipe 43 leads from the other side of the valve housing 41 into the bottom, and right-hand side of a pump 35 as seen in Figs. 1, 2 and 7; the pump being designated in its entirety by reference numeral 45.

Disposed within the container 25, adjacent the bottom thereof, is a pipe coil 50. This comprises a plurality of loops formed by a continuous pipe and 40 all loops lie in the same horizontal plane. As seen in Fig. 3, a flat metal plate 51 overlies the coil and supports the solidified refrigerant thereon. A pipe 52 extends from one end of the coil 50, through the rearward wall of the compartment 25, and is then directed upwardly through the insulation 28 and at its upper end opens into the bottom of a storage tank 53 containing the liquid refrigerant or "brine." Also, a pipe 55 leads from the top portion of the brine tank into the top left-hand side of the pump 45, and the circulating circuit for the brine is completed by a connecting pipe 56 leading from the other end of the pipe coil 50, and directed upwardly through the insulation 28 and connected to the bottom left-hand side of the pump, as seen in Figs. 2 and 6.

As seen in Figs. 1 and 3, the coils 50 lie substantially parallel, in close relationship to each other, and the plate 51 is disposed upon or adjacent their upper surfaces so as to provide for an even heat distribution or transfer to the solidified refrigerant.

Fig. 4 discloses, in cross section, an alternative form of coil construction, wherein pipes 50a are formed in rectangular or square cross sectional area and disposed parallel to each other in close relationship.

In Fig. 6, I have illustrated the pump 45 in detail, this pump comprises opposite side portions 60 and 61 of cup-like form and of like size, and disposed in edge to edge relationship, to form an enclosure. A flexible diaphragm 62 is disposed between the flanged edges of these parts 60 and 61 which are joined tightly together by bolts 63 through the flanges.

It will be noted that there is a hingedly mount-

ed flapper valve 58 within the shell 60, to automatically close the outlet of the pipe 56 against any return flow therein of the brine, as will be subsequently explained. Also, if found desirable, a back check valve 59 may be applied to the inlet into pipe 55 to cooperate with the valve 58.

Extended centrally through the diaphragm 62 is a bolt 65 held by a nut 66. The bolt head secures a lever 67, on the right-hand side of the diaphragm and a washer 68 is held beneath the nut on the other side; the washer, in turn, mounting a coiled spring 69, which bears against the base wall of the corresponding section 60 to press the diaphragm toward the opposite wall.

The section 61, closing the right-hand side of the pump, is provided with a port 70, through which the gas generated by evaporation of the solidified refrigerant is exhausted in operation of the pump. This port 70 is fitted with a 20 sleeve 71 formed at its inner end with a valve seat 71^a, against which a ball valve 72 is adapted to seat to seal the port. The ball 72 is actuated from a closed position to open position by the action of a mechanism including a pair of formed levers 75 and 76 which are mounted to oscillate on, and extend, respectively, upwardly and downwardly from a horizontal hinge pin 77 that is fixed in a bracket 78 that is rigidly fixed to the wall just below the port 70.

It will be noted that the lever 75 fixedly mounts a coiled spring 80 contained within a shallow cylindrical cup 81 that is fixed on the side of the lever facing the port 70; this spring mounts the ball and serves to yieldably hold it against the valve seat 71^a when in closed position. The cup 81 serves also to retain the ball 72 against displacement from operating position when the valve is open.

The levers 75 and 76 are provided at their swinging ends with laterally extending ears 75a and 76a respectively, connected, as seen in Fig. 7, by coiled springs 85. It will be noted also that the levers 75 and 76 are provided at their inner ends with short, angularly extending legs 75b and 76b respectively, which engage the base of the bracket 78 and thus operate to limit the outward travel of these levers when actuated by springs 85 to position to open the valve 72. It will be noted that the bracket 67 is of U-form and has its outer end extended to a position underlying the swinging end of lever 76 so that movement of the diaphragm will cause movement of the lever, for a purpose presently understood.

By reference to Fig. 7, it will be noted that the needle valve 41 is operated between open and closed positions by the thermostat 42. The valve housing is provided with a threaded mounting shank 41a that extends into the housing 90 of the thermostat, and this shank contains a needle valve stem 91 which extends into the thermostat housing. This valve mechanism may be of conventional construction, and is adjusted for proper operation and is then locked in place by the lock nuts 92 which are adjustable on the shank; it being understood that seating of the stem 91 is effected by means of a bi-metal thermostatic arm 95a so disposed for action against the needle member 91 that by upward pressure of the thermostatic arm 95a, the needle will close a gas relief outlet 41b in the valve, thereby to cause all the gas to be delivered to the pump through pipe 43. However, when the temperature is sufficiently lowered, the pressure on stem 91 will be

relieved, the stem will move away from port 41b, and gas will be by-passed to atmosphere and action of the pump will stop.

A thermostatic, bimetal spiral 95, provided with the extending lever portion 95a, is disposed beneath the valve stem 91, and is mounted by a supporting shaft 96. The shaft 96 extends rotatably through the housing wall to the exterior and there is provided with an indicator arm 97 overlying a calibrated strip 98 fixed on the housing. It will here be stated that the shaft 96 which, on its inner end, mounts the bimetal spiral 95 and on its end, the arm 97 is tight enough in its mounting so as not to be moved or rotated by the force of the spiral when it expands due to low temperatures but may be moved manually by the arm 97 so as to set the thermostat to operate the valve at any desired temperature, as will be determined by the position of the arm 97 relative to the calibrated strip.

It is desirable in the use of this apparatus that means be provided for controlling or limiting the flow of gas to the pump and for stopping flow when pressure in the refrigerant container falls below a predetermined amount; the reason for this being that when the gas pressure within the container is high there is a possibility of its compressing the spring 69 in the pump 45, and holding it compressed. This, of course, is only possible when the gas pressure is greater than the expansion force of the spring. Also, by closing the discharge line at a certain low pressure, such as a pressure that will just operate the pump 45, there will always be a sufficient supply of gas available to start the pump immediately when the thermostat by-pass valve is closed.

Therefore, there is interposed in the gas delivery pipe 40, a pressure regulating valve 210 and a needle valve 211, as illustrated in detail in Fig. 10.

The pressure regulating valve 210 is formed with a seat 212, against which a ball valve member 214 is adapted to close; the ball being actuated yieldably to closed position by a coiled spring 215. The retaining pressure of the spring may be varied by the adjustment of a stem 216 that is threaded through a cap 219 applied to the valve housing and which mounts the spring at its inner end.

The adjustment of the stem obviously makes it possible to determine the pressure at which the valve will close. The valve 211 is provided with a cap member 220 threaded into the valve housing and is provided with a threaded adjustable valve stem 221, which comprises at its lower end, a needle valve member 221a adapted to progressively restrict the passage 222, through the valve housing, until it is approximately closed. By such a provision, the flow of gas to the pump may be regulated or controlled with reference to a maximum high pressure through the valve 211, in that the flow is restricted and there is not ample time to build up a pressure great enough to hold the spring 69 compressed, thereby insuring continuous and uninterrupted operation of the pump when the thermostatic by-pass is closed.

The use of the device as described in the foregoing is as follows:

To charge the container 25 with the refrigerant, or "dry ice," the bar 34 is rotated by proper action of the handle 36, to relieve the pressure of the formed cams 35 on the lid 30, and permit removal of the rod ends from the slots in the brackets 32. The lid 30 may then be removed and the "dry ice" placed in the container whereupon the lid must be replaced and the container sealed.

It will here be stated that the insulation 28 around the ice chamber is a very essential feature of construction in that the refrigerant used is of such low degree of temperature; namely, about 109° C., below zero, that without it, the storage chamber in the cabinet would eventually reach approximately the same temperature, which would be much too cold for ordinary usage.

The pipe system and storage tank are assumed to be filled to proper level with a suitable liquid refrigerant or brine, which normally fills the left-hand compartment of the pump, as seen in Fig. 6.

As the "dry ice" absorbs heat from the plate 51 and coils 50, it evaporates, and the resultant gas builds up a pressure within the container 25 and also in the pipes 40 and 43, leading to the pump 45. Assuming that needle valve 91 is seated as in Fig. 7, it will be understood that, as this pressure increases, it pushes the diaphragm 62 from the position shown in Fig. 6 to the opposite side, thus to dispel the brine through pipe 55 into tank 53. The valve 58 closes automatically with this operation, and valve 59 opens. Then, when the diaphragm comes to rest, the valve 59 closes. As the diaphragm is moved by the gas pressure to the left side of the pump, the upturned end portion of the lever 67 lifts the lever 76 and when the lever 76 passes over its dead center position, the springs 85 cause the valve mechanism to snap open, throwing the valve ball 72 away from the port 70.

Then, when the valve ball 72 is lifted from valve seat 71', the gas confined in the pump chamber is exhausted through port 70, and the spring 69 will then act to move the diaphragm 62 back to the original position. Incident to this return movement of the diaphragm, the head of bolt 65 will engage the lever 76 and move it back across the dead center line in such manner as to cause the valve mechanism to close the valve 72 against its seat, thus to close the pump for a subsequent building up of gas pressure therein.

It will here be mentioned that I do not confine the valve mechanism to the ball type shown, but fully anticipate that a needle valve may be used with satisfactory results. Therefore, in the appended claims, the use of the term "valve" in referring to this particular apparatus is to be construed broadly as any suitable type valve of an equivalent nature, for closing port 70.

This cycle of operations is repeated periodically, thus drawing the brine from the coils 50 into the diaphragm pump, and then forcing it into the tank 53. Because of this pumping action brine is drawn from the tank 53 into the coils 50 and is there cooled. The heat extracted from the brine causes the "dry ice" to evaporate to generate gas. The plate 51 that overlies the coils 50, in contact therewith, provides for an even dissipation of heat from the coils, and as the "dry ice" is evaporated evenly by this plate 51, it feeds down evenly. It is therefore obvious that the interior of the storage cabinet may be cooled rapidly, in that the warmer the brine is, the faster the "dry ice" will be evaporated, thereby speeding up the operation of the diaphragm pump.

Furthermore, when the temperature of the storage cabinet reaches the temperature for which the thermostat is set, the needle valve 91 will be opened by movement of the extending portion 95a of the bimetal lever. The opening of the port 41b bypasses the flow of gas and consequently stops the operation of the diaphragm pump. When the temperature rises sufficiently to cause the thermostat to close the port 41b, pumping is

resumed. However, there are certain possibilities of the pump being rendered inoperable by a very high gas pressure being built up in the container 25; for instance, subsequent to its being recharged with a fresh supply of "dry ice," and the whole interior of the cabinet being at a comparatively warm temperature. On such occasion, the heat transfer is rapid and the "dry ice" evaporates rapidly, and such pressures might be high enough as to prevent the spring 69 from operating the diaphragm, as previously stated with reference to the pump operation.

The regulating valve 211 may be adjusted so that the flow of gas therethrough is slow enough that a pressure great enough to hold the spring 69 compressed does not have sufficient time to build up, thereby insuring a continuous and uninterrupted pumping operation.

Furthermore, the pressure valve 210 retains a predetermined gas pressure within the container, so that when the port 41b in the by-pass valve is opened, the gas pressure in the tank will be reduced to the aforementioned predetermined value, the excess gas escaping. Then, when the needle 91 is actuated by the thermostat to close the port 41b, the pump will operate substantially immediately, upon any increase of gas pressure, and thereby eliminate the period of inoperation necessary to build up, by evaporation of the "dry ice," the gas pressure that is retained in the compartment 25 by the said valve 210. It is obvious that a more efficient pumping and circulating cycle is thereby insured by these two valves, and it is also obvious that a regular or even temperature may thus be maintained with this type of refrigeration, and that a very broad range of refrigerating temperatures is available.

In Fig. 9 is diagrammatically illustrated an alternative arrangement known as a "one pipe system." It is to be understood that in this system, the compartment 25 or container for the evaporable refrigerant referred to as "dry ice" may be like that previously described in principle, and the tank for storage of brine also may be like that previously described. However, only a single pipe 100 extends from the brine tank 53 to the cooling coils 50 and a pipe 101 connects the coils 50 with the liquid receiving side of the diaphragm pump 45; this connection corresponding to the pipe 56, shown in Fig. 6, but with the back check valve 58 and the pump outlet pipe 55 eliminated. A gas pipe 103 leads from the container 25 to the gas side of the pump which would be as illustrated in Fig. 6.

To control the flow of gas, a thermostatically controlled valve device 105 corresponding to the parts 41 and 42 of Fig. 7, would be applied to pipe 103.

Thus, it will be understood that in this alternative system, the flow of liquid has a reciprocating action rather than of circulation, for the diaphragm pump under the influence of generated gas, will operate to intake and then expel from the pump the cooling liquid through the pipe system, thus to periodically recharge the coils of the system with brine from the tank; the brine thus being kept cooled by the refrigerant.

In Figs. 11 and 12 are illustrated two more alternate means for forced circulation of the cooling brine through the medium to be cooled. With reference to these alternate forms of construction of the brine pump, it will be understood that the pump 45 as in Fig. 6 provides what may be termed an "intermittent" movement or circula-

tion of the brine in the cooling system, and furthermore, that the circulating means provided for in the pump illustrated in Fig. 11 is also of this intermittent movement or circulation type, while the means provided for in the pump illustrated in Fig. 12 is what may be termed a continuous flow system.

Referring now to Fig. 11, the pump mechanism is designated in its entirety by the reference numeral 225, and it comprises a cylindrical housing 226 containing a reciprocating piston 227, provided with a piston rod 228 slidably disposed within a bearing 229 in the upper end wall of the housing. This rod is provided with shoulders 228a and 228b which operate to limit the reciprocal travel of the piston. Beneath the piston 227 is a compression spring 230, adapted to lift the piston within the cylinder, as will be subsequently explained.

It will be noted that the pipe 43 which delivers the gas from the refrigerant container 25 to the pump is operably connected to the cylinder 226 above the piston 227, and that the brine pipes 56 and 59 are operably connected to the cylinder 226 below the piston 227, and also that there is a back check flap valve 231 adjacent to the connection of the pipe 56, and a back check flap valve 232 adjacent to the connection of the pipe 56 to provide a one-way flow of the brine. The same valve mechanism illustrated within the diaphragm valve in Fig. 6 is associated with the reciprocating piston pump, and it will not here be referred to in detail. However, any other valve mechanism may be used that will accomplish the desired action.

An upwardly projecting boss 232a on the upper side of the piston 227 is adapted to contact the valve lever arm 76 and operate the valve ball 72 to a closed position, and a chain connection 233 is substituted for the lever 67 to open the valve at the lower limit of travel of the piston 227, this chain being connected to the lever 76 and to the boss 232a.

In the other alternative form illustrated somewhat diagrammatically in Fig. 12, a turbine 235 operates a centrifugal pump 236 that is connected thereto by a common shaft 237. The gas delivery tube 43 is connected to the turbine, so that the gas is delivered through a nozzle or orifice 238 and impinges upon the blades 239 of the turbine. The operation of the centrifugal pump 236, as well as the turbine 235 is well known, and therefore a further description is deemed unnecessary. However, it will be pointed out that in the use of either of the pumps 45 or 225, the circulation of the brine is intermittent, whereas when the centrifugal pump 236 is in connection with a suitable gas propelled driving means, such as the turbine 235, the circulation of the brine is a steady or continuous flow while the pump is in operation.

In Fig. 13 is illustrated still another modification of the system; this system eliminating the gas actuated pump. In this arrangement, the coils 50 are supplied with liquid from tank 53 through a pipe 106, and the liquid delivered back into the brine tank through a pipe 107. A goose-neck turn, or vertical loop 108 is provided in pipe 106, and this contains a back check valve 109. A gas connection is provided through a pipe 110 between the container 25 and the top of the goose-neck between the back check valve and coils 50. This gas connection is equipped with a back check

valve, designated at 111, for preventing back flow of the liquid into the container 25.

In this system, the gas discharged from container 25 is forced into the pipe coils 50 through pipe 110, through coils 50, and pipe 107 into tank 53, and is expelled finally through a vent as at 112, in the top of tank 53. The operation of this system is as follows: When gas pressure is built up in the pipe system, it forces, ahead of the gas, the liquid, displacing it from the coils 50, and finally discharging it into the tank through pipe 107. When the brine is thus discharged, the gas escapes into tank 53 and the relief of this pressure in the coils permits the back check valve 109 to open, thus allowing the coils to again fill with fresh brine from the tank through pipe 106.

In this latter system, a thermostatically controlled valve device 113 controls the admittance of brine into pipe 106; the valve closing when a desired temperature has been reached and opening when the temperature rises above this desired degree.

In Figs. 14 and 15 respectively there has been illustrated certain means for preventing siphoning of liquid, or gravity flow of liquid, back from the tank 53 into the compartment 25. In Fig. 14, an auxiliary tank 190 is provided alongside of tank 25 and of sufficient volume to hold the normal supply of liquid in tank 53. In the event the liquid siphons back, it will be retained in tank 190 and not flow into the container 25. Then, when gas is created in container 25, the liquid in tank 190 will be forced up into tank 53. Connections 191 and 192 are provided between upper and lower ends of tank 190 respectively with the container 25 and pipe 193 to the tank 53.

In Fig. 15 is a similar device wherein a tank 195 is provided alongside of tank 25 and is connected by a very small gas port 196. A gas jet nozzle 197 opens from the bottom of tank 196 into pipe 198, leading to tank 53. The theory here is that while port 196 is large enough for gas delivery, it is too small for liquid to flow back through to any extent while the tank 25 is being recharged.

Having thus described my invention, what I claim as new therein and desire to secure by Letters Patent is:

1. In a refrigerating system, a medium to be cooled, a closed container for an evaporable refrigerant, a gas vented tank containing a supply of liquid cooling medium, a pipe system connected with the tank providing a one-way liquid circuit passing in heat exchange proximity to the medium to be cooled and to the refrigerant, a back check valve in the pipe line at one side of the refrigerant container, and means for discharging gas under pressure from the container into the pipe system at one side of the valve to dispel the cooled liquid therefrom into the tank; said back check valve being adapted to open when pressure of gas is removed by reason of its exhaustion into the tank, to permit recharging of the pipe system with liquid from the tank.

2. A system as in claim 1, wherein a thermostatic valve controls the admittance of the liquid from the tank into said pipe system.

3. In a refrigerating system of the character disclosed, a medium to be cooled, a closed container for an evaporable refrigerant, a storage tank for a supply of liquid cooling medium disposed above the said container, a liquid circuit connected at its opposite ends to receive from 70 and deliver liquid into the tank, and extending

through the medium to be cooled and through the said refrigerant container for heat exchange, a reservoir located below the level of the storage tank, a gas delivery connection between the refrigerant container and top of the reservoir, and a gas connection from the reservoir into the circuit for delivery of gas under pressure to create circulation of the liquid in the circuit; said reservoir being adapted to retain any liquid that should be syphoned or otherwise caused to flow thereinto through its gas connection with the liquid circuit incident to lack of gas pressure in the refrigerant container.

4. A system as in claim 3 wherein the gas connections between the closed container and liquid circuit are so located relative to vertical spacing that gas pressure created in the closed container will operate on the liquid in the reservoir, as to displace it back into the liquid circuit and storage tank.

5. A system as in claim 3 wherein the gas connecting passage between the closed refrigerant container and reservoir is relatively small, thereby to greatly retard any flow therethrough of liquid.
